CLAIM

We claim the ornamental design for a desk, as shown and described.

DESCRIPTION

FIG. 1 is a top front perspective view of a desk;

FIG. 2 is a bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings illustrate portions of the desk, which form no part of the claimed design.

1 Claim, 8 Drawing Sheets
